(57) **CLAIM**

The ornamental design for a thermometer, as shown and described.

DESCRIPTION

FIG. 1 is a front perspective view of a thermometer;
FIG. 2 is a rear perspective view of the thermometer of FIG. 1;

FIG. 3 is a front elevation view of the thermometer of FIG. 1;

FIG. 4 is a rear elevation view of the thermometer of FIG. 1;

FIG. 5 is a left side view of the thermometer of FIG. 1;

FIG. 6 is a right side view of the thermometer of FIG. 1;

FIG. 7 is a top plan view of the thermometer of FIG. 1;

FIG. 8 is a bottom plan view of the thermometer of FIG. 1;

FIG. 9 is a front perspective view of a second embodiment of a thermometer with a cap removed;

FIG. 10 is a rear perspective view of the thermometer of FIG. 9;

FIG. 11 is a front elevation view of the thermometer of FIG. 10;

FIG. 12 is a rear elevation view of the thermometer of FIG. 10;

FIG. 13 is a left side view of the thermometer of FIG. 10;

FIG. 14 is a right side view of the thermometer of FIG. 10;

FIG. 15 is a top plan view of the thermometer of FIG. 10 with the cap removed for illustrative purposes; and,

FIG. 16 is a bottom plan view of the thermometer of FIG. 10.

The evenly broken lines (dash-dot lines) shown in the Figures are only for illustrative purposes to show visible environmental structure and form no part of the claimed invention. Likewise, it is contemplated that any portion of one or more of the solid lines shown in any one or more of the Figures can be converted into evenly broken lines to form no part of a claimed invention.

The boundary lines (as opposed to the evenly broken lines) shown in various ones of the Figures in dash-dot-dot form do not exist in reality in the respective article embodying the design and are only for illustrative purposes to show bounds of the claimed design. It is understood that the claimed design extends to the boundary lines but does not include the boundary lines or the portion of the article therein and/or beyond the boundary lines.
